REVERSIBLE CAP

Patricia S. Marchand, Corsicana, Tex.

Application May 18, 1953, Serial No. 25,041

Term of patent 7 years

(Cl. D3—13)

To all whom it may concern:

Be it known that I, Patricia S. Marchand, a citizen of the United States of America, residing at Corsicana, State of Texas, have invented a new, original, and ornamental Design for a Reversible Cap, of which the following is a specification, reference being made to the accompanying drawing, forming a part hereof.

Fig. 1 is a top perspective view of a reversible cap showing my new design,

Fig. 2 is a bottom perspective view thereof,

Fig. 3 is a top perspective view of the reversible cap shown in Fig. 1 as it appears in reversed position, and

Fig. 4 is a bottom perspective view thereof.

The drawing is shaded to indicate contrast.

I claim:

The ornamental design for a reversible cap, as shown and described.
